H. LUYKEN

CUPOLA WITH FORE HEARTH

Filed Feb. 26, 1924

Hugo Luyken

Inventor:

By Byers, Townsend & Bricklehurst
Atty's

UNITED STATES PATENT OFFICE.

HUGO LUYKEN, OF BIELEFELD, GERMANY.

CUPOLA WITH FOREHEARTH.

Application filed February 26, 1924, Serial No. 695,259, and in Germany March 5, 1923.

In order to utilize the molten iron from a cupola to the best advantage, it is necessary to have it as free from slag as possible, otherwise slag is likely to enter the mold

5 with the iron and thus ruin the casting. It is particularly necessary to keep slag away from molten iron which is to be subjected to chemical action to refine it, as otherwise this purification of the metal is injuriously 10 affected, if not prevented altogether. This condition is very marked in the case of the desulphurization process by means of alkalies.

In order that molten iron free from slag 15 may be taken from a cupola it is not sufficient, as has been hitherto proposed, to provide the cupola with an overflow discharge channel even if the level of the overflow and consequently also that of the metal within the 20 cupola is kept fairly high over the discharge opening at the bottom of the cupola. Experience has shown that in spite of such overflow channel under certain conditions which are out of control of the operator 25 the slag finds its way to the overflow. The purpose of this invention is to overcome this difficulty and the desired effect is secured by throttling the stream of molten metal in its flow from the cupola to the overflow channel. Although this throttling action 30 does not affect the equilibrium between the column of molten metal within the overflow channel and the column of molten metal, its slag layer and the blast pressure within 35 the cupola, nevertheless the throttle prevents occasional fluctuations in pressure occurring during the run of the cupola from forcing slag from the cupola to the overflow. The action of the contraction in the discharge 40 channel for throttling purposes is further enhanced if the cross section of the upright overflow channel is considerably enlarged compared with the throttled connecting channel leading from the cupola to the said 45 upright overflow channel.

The invention is illustrated on the accompanying drawing which shows one form of

cupola with fore-hearth or ladle connected with the cupola by an interposed upright overflow channel with a throttled feed 50 branch at its lower end.

The cupola shaft is designated *a*, the fore-hearth *b*, the contracted connecting channel *c*, the upright comparatively wide overflow channel *d*, and the channel for the overflow 55 at the upper end of channel or chamber *d* is designated *e*. The bridge, over which the iron flows is designated *g*. The reference character *f* designates an opening in the side of the fore-hearth, which serves to 60 allow the introduction of refining materials, as for instance a desulphurizing material. An opening *h* in the shell of the cupola serves to draw off the slag from within.

The cupola shaft and the fore-hearth, together with the connecting channels *c*, *d*, *e* 65 form a set of communicating pipes which allow the molten metal in the cupola coming from the material charged to act in accordance with the laws governing the flow of 70 liquids in pipes.

The contracted channel *c*, however, prevents any cumulative forces caused by pressure fluctuations within the cupola from becoming effective within the pipe system, and 75 thus effectively prevents possible depressions in the slag level within the cupola which would force slag through the channel *c*, and into the fore-hearth by way of the upright chamber *d*. 80

What I claim is:

In a furnace comprising a cupola and a fore-hearth, a vertically extending channel having the upper end thereof in open communication with the upper portion of said fore-hearth, and a passage of restricted cross-section between the lower end of said channel and the shaft of said cupola, whereby momentary fluctuations of the level of the molten metal in said cupola shaft are 85 damped. 90

In testimony whereof, I affix my signature.

HUGO LUYKEN.
